Primary Examiner — Karen E Eldridge Powers(74) *Attorney, Agent, or Firm* — Vladimir Postnikov(57) **CLAIM**

The ornamental design for a heated brush, as shown and described.

DESCRIPTION

FIG. 1 is a perspective view of a heated brush showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof;

FIG. 8 is a bottom plan view thereof;

FIG. 9 is an enlarged view of the encircled portion in FIG. 1;

FIG. 10 is an enlarged view of the encircled portion in FIG. 3; and,

FIG. 11 is an enlarged view of the encircled portion in FIG. 5.

(Continued)

(Continued)

The dash-dot lines in FIGS. 1, 3, 5, 9, 10 and 11 illustrate the boundaries of the enlarged view indicators and form no part of the claimed design.

1 Claim, 11 Drawing Sheets
